Application October 21, 1953, Serial No. 387,416

3 Claims. (Cl. 197—138)

This invention relates to printing machines and more particularly to an improved carriage for a typewriter, or similar machine.

It is a first object of this invention to provide an improved carriage wherein paper feed rollers are releasably engageable with the platen of the carriage in such a manner that feed roller pressure is always normal to the peripheral surface of the platen.

It is a further object of this invention to provide an improved means for releasing and restoring the feed roll pressure against the platen.

It is a still further object of this invention to provide an improved structure for mounting paper feed rolls on a movable carriage.

Other objects of the invention will be pointed out in the following description and claims and illustrated in the accompanying drawings, which disclose, by way of example, the principle of the invention and the best mode, which has been contemplated, of applying that principle.

While the following description relates primarily to typewriters, it is to be understood that such a machine is not intended as a limitation, but rather has it been chosen simply as an example to explain more clearly the operating features and principles of this invention.

Briefly, this invention relates to an improved office machine carriage structure wherein the paper feed rolls, when in driving position, always exert a force normal to the platen. The pressure of the feed rollers against the platen may be relieved through the operation of a single handle, and the pressure may be restored by a converse operation of the same handle. Further, the carriage is provided with an improved paper bail which cooperates with the end covers of the carriage in such a manner that the bail cannot be positioned in operative arrangement with the platen except in such a manner that the work sheet tends to be smoothed onto the platen. This is accomplished through an improved arm construction for the bail arranged to cooperate with cam surfaces on the side covers of the carriage. The improved carriage structure also includes a new line spacing mechanism which is so pivoted on the carriage end frames as to insure a positive and unique relationship with the platen ratchet when the line spacing link is operated in response to a clutch controlled pull on a tape during a carriage return operation.

In the drawings:

Fig. 1 is a plan view of the left half of a typewriter carriage.

Fig. 2 is a plan view of the right half of the typewriter carriage.

Fig. 3 is a side elevation through plane 3—3 of Fig. 1 taken in the direction of the arrows.

Fig. 4 is a side elevation through plane 4—4 of Fig. 1 taken in direction of the arrows.

Fig. 5, like Fig. 3, is a side elevation through plane 3—3 of Fig. 1 taken in direction of arrows, but with some of the mechanisms removed for clarity.

2

Fig. 6 is a perspective view of the improved feed roll support structure.

Fig. 7 is an exploded view of a portion of the feed roll supporting structure of Fig. 6.

5 For simplicity of description, the following specification will be broken into four parts, namely, (a) general structure, (b) supporting structure for feed roller; (c) paper bail structure; (d) line spacing mechanism.

(a) GENERAL STRUCTURE

10 With particular reference to Fig. 4 of the drawings, a carriage 1 is shown supported by means of suitable bearings 2 in a typewriter base member 3. Such an arrangement supports the carriage for conventional transverse or letter spacing movement.

The carriage has a foundation or frame comprising a pair of parallel runner elements 4 interconnected, as by welding, by a lower plate member 5 and an upper plate member 6, thereby presenting a rigid box-like frame construction that resists vertical bouncing or oscillation of the carriage and insures the linearity of a printed line.

The carriage frame is provided with suitable end plates 7, 8 (Figs. 1, 2) which support platen 9 (again Fig. 4), 25 a paper bail 10, line spacing mechanism 11 (Fig. 3), and the usual assemblage of conventional carriage parts.

Referring now to Figs. 1 and 2, a platen suspension or slideable element 20 is shown as comprising a pair of slide plates 22, 24 interconnected by a pair of shafts 26, 28. Plates 22, 24 are mounted for sliding motion in planes parallel to end plates 7, 8 by means of rivets or studs 23 (see Figs. 3, 4) which extend from the end plates and through suitable corresponding elongated slots 25 in the side plates 22, 24.

35 In this manner, the slideable element 20 is mounted for movement in a direction transverse to the axis of the platen, and the purpose of this structure is to provide for the movement of the platen, transverse to its axis, towards and away from the machine single printing position. The intention is that when a large number of carbon copies are to be made, the platen should be removed from the printing position as far as possible, while when just a single work sheet or single copy is to be made, the platen should be moved forwardly towards the printing position, and in this manner, irrespective of the thickness of the work sheet pile, the first sheet can be maintained in an identical position relative to the print position. The operating mechanism for this transverse movement will hereinafter be described.

The platen 9 is supported in suitable bearing-like grooves or notches 34 (Fig. 4) formed in end plates 22, 24. The notches have a width adequate to accommodate the shaft of the platen, and suitable bearing locks are provided by hooked brackets 40 (see Fig. 5) pivoted as at 42 on the end plates 7, 8 respectively.

50 Each bracket 40 has a slot 44 therein, while a suitable crank arm 46 is pivoted at 48 on the end plates 7, 8. Each crank arm 46 has an arm 50 which is slideably connected by means of pin 52 to the bracket 40 at slot 44. In this manner, rotation of the crank arm 46 permits pin 52 to slide in the slot 44, and thereby rotate bracket 40 about its axis 42 into and out of the platen shaft locking position (both positions are shown in Fig. 5). When bracket 40 is rotated counterclockwise to its phantom position shown in Fig. 5, the platen can be readily removed from its supporting plates.

55 Shaft 28 of suspension element 20 (Fig. 2) is furnished with integral cams, 47, 49, at its point of engagement with the plates 7, 8 respectively. With this structure, the rotation of shaft 28, because of the cams, is arranged to slide the suspension element 20 rearwardly or forwardly to increase or decrease the effective platen diameter.

Shaft 28 (Fig. 2) has an extension 54 that protrudes through plate 8 to support a crank arm 56. A link 58 connects crank arm 56 to a pivot point 60 in an adjusting arm 62, whereby pivotal movement of arm 62 rotates shaft 28 and varies the position of the cams in contact with plates 7, 8.

(b) FEED ROLLER SUPPORTING STRUCTURE

Referring now to Fig. 6, the feed roller structure is shown supported on shafts 26 and 28. Specifically, depending upon the length of the carriage, a plurality of bracket units 64 are suspended between the shafts 26 and 28. In the instant situation, three of the bracket units are shown.

As shown in the exploded view in Fig. 7, each bracket unit comprises a pair of parallel support plates 66, 68, an actuated or rear support arm 70 and a follower or front support arm 72.

The shaft 26 is equipped with cammed surfaces 74 in alignment with each of the bracket units 64. Specifically, as more particularly shown in Fig. 7, the rear support arm 70 normally rides close to the flat surface 76 of cam 74, and this is the relative position of the parts when the support arms 70 and 72 are applying pressure through the feed rollers to the platen 9.

Upon rotation of shaft 26, however, the cam portion 74 slides on the rear support arm 70 to rotate it clockwise relative to its position shown in Fig. 7 to move it and its associated rollers, hereinafter described, out of engagement with platen 9.

It will be noted that the rear support 70 carries a tail 78 positioned for cooperation with a shoulder 80 on the front support 72. Accordingly (Fig. 7), when the rear support 70 is rotated clockwise about its support, the tail 78 engages the shoulder 80 to rotate the front support 72 counterclockwise.

In order to furnish suitable pivotal suspension for the rear and front supports 70 and 72, and simultaneously to bias them for holding the drive rollers into engagement with the platen 9, a unique support is provided for their mounting. Specifically, bushings 82 and 84 respectively are secured in some manner, as by welding, to the supports 70 and 72. Each bushing has a pair of collars that extend through apertures in the both plates 68 and 66, where they are held in place by C rings 69 (Fig. 6) which slide into peripheral grooves in the bushings. In this manner, a bearing support is provided for both the rear support 70 and the front support 72, permitting them to rotate relative to plates 66, 68.

Each of the bushings 82 and 84 has centrally formed therein a slot 83, 85 (Fig. 7) for receiving a strip spring 86, 88 respectively.

It will be noticed from Fig. 6 that each of the strip springs 86 and 88 is twisted along its axial length. The purpose of the spring is to bias the rear and forward supports 70, 72 into engagement with the platen. Accordingly, a pair of support brackets 90, 92 are supplied to lock the spring at predetermined positions along its length, and then the spring is twisted relative to these fixed positions. Since these springs fit through slotted apertures 83, 85 in the bushings 82, 84, it follows that with suitable clockwise and counterclockwise twists in the spring, the rear arms 70 will be urged normally counterclockwise and the forward support 72 clockwise into engagement with the platen.

In Fig. 6, screws 94 are employed to secure the springs 86 and 88 to the brackets 90 and 92. The purpose of the screws is to wedge the springs against associated ears 96 which are upstanding from the brackets 90 and 92. In this manner, by adjusting the turns of the screws 94, the amount of twist or tension in the springs 86 and 88 can be controlled and consequently the tension on each of the supports 70 or 72 can be regulated for uniform pressure between the feed rollers and the platen.

The supports 90 and 92 which regulate the twist in

5 springs 86, 88, must be free of the carriage frame in order that they may move transversely with suspension element 20. Accordingly, the supports 90 and 92 are suspended in front by integral collars 98 which encircle the forward shaft 28. Their only rear support is provided by the springs 86 and 88. That is, the springs 86 and 88 are relatively stiff and tend to restrain rotation of the supports 90 and 92 about the shaft 28.

Feed rollers

10 Two sets of feed rollers are provided to hold a work sheet in driving relation with the platen, namely rear feed rolls 100 and the front feed rolls 102. In order to support them, a pair of shafts 104 and 106 are carried respectively in the outer tips of the arms 70 and 72. Specifically, the outer ends of the supports 70 and 72 are slotted or bifurcated (Fig. 7) at 109 and 111 (Fig. 7) so as to receive the shafts 104 and 106 respectively.

15 Since the rear shaft 26 simultaneously cams each of the rear brackets 70, which in turn control the position of the front brackets 72, it follows that shafts 104, 106 carried by brackets 70, 72 respectively will be maintained parallel to the axis of the platen. This is an important feature, since it prevents skewing of a work sheet.

20 To control endwise movement of the feed rolls, a pair of them are secured to a collar-like shaft 108 which in turn fits over the shafts 104 and 106 respectively and between a pair of the bracket members 64. This structure holds the feed rollers freely rotatable and yet limits their endwise or axial movement.

25 To provide for the rotation of the rear shaft 26 for the camming action required to release the pressure on feed rollers, it is extended through the slide plate 24 where it is equipped with a link-like collar 114 (Fig. 6). An intermediate link 116 connects a crank pin 118 on collar 114 to a stud 120 carried by an operating arm 122, which in turn is supported on a pivot stud 124 carried by the slide plate 24.

30 With this structure, a forward pull on the upper end of operating arm 122 as viewed in Fig. 6 produces a counterclockwise rotation of shaft 26 which in turn through cam 74 rotates rear supports 70 clockwise and the front supports 72 counterclockwise. Any rotation of the supports 70 and 72 puts further tension into the spring members 86 and 88 respectively. If the arm 122 is rotated far enough, then the high dwell portion 123 (Fig. 7) of the cams 74 will be in contact with each of the rear supports 70 thereby locking the supports and their associated rollers 100 and 102 out of engagement with the platen. In this position, paper can be inserted between the feed rollers and the platen whereupon by restoring the arm 122 to its position as shown in Fig. 6, the feed rollers are again brought into driving contact with the platen.

35 In Fig. 6, the plates 68 are shown having upwardly extending arms 126 that are notched as at 128 and provided with fingers 130 for supporting springs 132. (Both of the plates 66 and 68 at the central bracket unit 64 are provided with this arrangement.)

40 The function of the upstanding arms 126 is to support a guide or feed plate 134 which, as shown in Fig. 6, is rotated clockwise from its normal position. The guide plates 134 have slots 136 for interlocking with the notches 128 thereby to provide a hinge-like relationship. The plates 134 also have apertures 135 to accommodate the rear feed rollers 100 and notches 137 to accommodate the front feed rollers 102. Springs 132 bias plates 134 normally into engagement with the platen 9.

45 By thus supporting the plates 134, they are readily removable for access to the spring adjusting screws, and yet they are normally suspended to guide a sheet of paper around the platen and past both sets of feed rollers 100 and 102 respectively.

(c) PAPER BAIL

50 It has been mentioned that one of the objects of this

invention is to provide an improved paper bail which is so constructed that it tends to smooth paper onto the platen to prevent rumpling or crinkling of the work sheet. In order to accomplish this objective, the paper bail 10 is mounted on a support rod 140 (Figs. 3, 5) which in turn is suspended in the two slide plates 22 and 24.

The paper bail comprises hinge arms 142, extension arms 144, a cross bail 145, spring arms 146 and suitable interconnecting structure.

Each hinge arm 142 is provided with a bearing-like aperture 147 for mounting on the support rod 140 to which they are brazed adjacent each of the slide plates 22, 24, respectively.

Each hinge arm is provided with a pin hinge 148 for a hinged connection with each extension arm 144 respectively. The pin hinge 148 simply extends through suitable apertures in the hinge arm and the extension arm so as to interconnect the two arms while permitting rotation of one relative to the other. The extension arms 144, however, are each provided with a lock 150 which, in effect, is a bent over ear that lies across the plane of the hinge arms 142 to limit the clockwise rotation (as seen in Fig. 5 of the extension arm about the hinge pin 148).

Each extension arm 144 has a rearward extension 151 beyond the hinge pin 148 which includes the extension arm bearing 152 that is positioned for sliding contact with spring arm 146 hereinafter described.

A pair of spring arms 146 are supported for rotation in planes adjacent and parallel to the slide plates 22, 24, respectively by means of pivot studs 156 which extend outwardly from the slide plates 22, 24 respectively. A coil spring 158 is wrapped around each of the pivot studs 156 with its end 160 connected to a slide plate and its opposite end 162 connected to the spring arm. In this manner, the spring arms are biased clockwise as viewed in Fig. 5.

Each of the spring arms has an "up" surface 164 and a "pull" surface 166 which are engageable with the extension arm bearings 152. Specifically, the extension arm bearings overlie the plane of the spring arm 146 and because of the bias of springs 158, either the "up" surface 164 or the "pull" surface 166 is always in contact with the spring arm bearings 152.

In view of the fact that the extension arm bearings 152 are mounted on a protrusion of the extension arm 144, it can be appreciated that, as shown in Fig. 3, the tension in spring arm 146 acting on the extension arm bearing 152 tends to rotate the extension arm counterclockwise and into engagement with the platen. That is, the cross arm or bail 145 carrying suitable rollers 170 (a structure hereinafter to be described) is forced into engagement with the platen. It can be appreciated that since the pull arm 166 (in its solid line position shown in Fig. 3) has the form of an inclined plane, and since it is biased clockwise by spring 158, the spring arm bearing 152 will tend to be forced down this plane and thereby exert a rearward pull on the extension arms 144, which rearward pull causes rollers 170 to smooth a work sheet onto the platen.

However, if the extension arm is pivoted clockwise about hinge 148 until the lock 150 prevents further rotation (see Fig. 5) and if the extension arm 144 and the hinge arm 142 are then rotated as a unit about the axis of support rod 140, the spring arm bearing 152 will roll up the pull surface 166 towards the apex 172. At this stage, the spring arm 146 acting on the spring arm bearing 152 will tend to rotate the extension arm clockwise about the hinge pin 148, but since the two arms are locked relative to one another by the lock 150, the "pull" surface 166 simply maintains the extension arm rotated to that position shown in Fig. 5, wherein it is lifted out of the way of the platen.

To bring the bail rollers 170 into engagement with the platen, the cross arm 145 is pulled forwardly where-

upon the extension arm and the hinge arm rotate as a fixed unit with support rod 140 until a guide stud 174, carried by hinge arm 142 (shown in Fig. 2) strikes the slide plate 24 thereby preventing further counterclockwise rotation of the hinge arm units.

At this point, since the rotation of the hinge arm is blocked by the guide stud 174, the extension arm will now rotate about hinge pin 148 counterclockwise until this motion is interrupted by the interaction of a cover bearing 176 (Fig. 3) carried by extension arm 144 with a cover guide cam 178 which is formed on a housing 179 that encloses carriage end plates 8, 22 and 9, 24 respectively. At this step, the bail will stay in position held by the "up" surface 164 of spring arm 146 until pushed by the operator past point 172 when pull surface 166 of the spring arms 146 will act on extension arm bearing 152 to pull the rollers 170 on cross bail 145 to the rear and into engagement with the platen. The motion of the cross bail 145 is guided, however, by the interaction of the cover bearing 176 with the cover guide cam 178. That is, the cover guide cam is so shaped that as the cover bearing 176 rides on it due to the rearward pull exerted on the extension arm 144 by the pull surface 166 of spring arm 146, the cross bail 145 moves up a plane including the inclined surface surface 180 of the cover guide cam 178; thus, the rollers 170 tend to smooth the paper onto the platen to prevent any bulging or wrinkling of the work sheet.

In order to remove the bail from the work sheet for erasures, the operator simply pulls cross arm 145 forwardly to expose that part of the work sheet which has just been printed. After the erasure, the operator releases the cross bail 145, and it will be pulled backwardly by the interaction of the spring arm 146 with the extension arm bearing 152, and again the rollers tend to smooth the paper onto the work sheet. The pulled out, or erasure position of the bail is shown in phantom in Fig. 3 of the drawings. In the erasure position of the bail, the "up" surface 166 of spring arm 146 is in engagement with extension arm bearing 152; which interaction wedges the bail into the erasure position until it is released by pushing bearing 152 over the crest 172 of the spring arm 146.

To bring about the desired interaction of the cover bearing 176 and the cover guide cam 178, the cover bearing is supported by a pin 182 which extends outwardly from the extension arm 144 whereby the pin and the bearing are so positioned with respect to the cover guide cam that the desired movement of the extension arm and the cross bail 145 is brought about. That is, the cover bearing slides up surface 180 wherein rollers 170 smooth the work sheet onto the platen, and then the cam surface falls away to permit roller 170 to engage the platen.

55 (d) LINE SPACING MECHANISM

In the prior art, and with particular reference to U. S. Patent 1,957,322, Crumrine, the general principles of line spacing mechanisms are described. Specifically, Crumrine's patent shows how a disc clutch is energized by applying axial pressure between slipping discs, to exert a pull on a tape which tape performs two functions, namely, effecting a carriage return and the effecting of a line spacing mechanism. The present invention relates to an improvement of the line spacing mechanism as activated by a pull tape under the influence of a disc clutch such as that described in the aforementioned patent.

Referring now to Fig. 3, a hook-shaped member 177 is suspended at one end for pivotal movement about a pin or stud 179 which in turn is mounted in the slide plate 22. The opposite end 181 of the hook member 177 is connected as at the pin 183 to tape 184. The latter tape is the one which brings about a carriage return upon the energization of the clutch as disclosed in U. S. Patent 1,957,322, Crumrine. In this invention,

however, a pull on tape 184 will rotate the hook member 177 clockwise about pin 179. The hook shape is provided in member 177 in order that it may partially encircle the platen shaft. In order to maintain hook member 177 in its normal or rest position as shown in Fig. 3, a roller bearing 185 is secured to the hook member 177 for contact with a dog 186. The latter is biased by a spring, not shown, but lying behind spring 188 which is supported about stud 190 along with the dog 186 to bias the dog 186 clockwise into engagement with the bearing 185 on the hook member 177.

The normal or rest position of the hook member 177 is determined by a certain plate 192 (Fig. 5) which is pivotally supported by pin 194 carried by slide plate 22. Specifically, a space determining arm 196 is mounted to be rocked about a stud 198. Arm 196 carries a pin 200 which in turn is engageable with a slotted aperture 202 in the plate 192. Consequently, clockwise rotation of the arm 196 about the pin 198 causes pin 200 to engage one of the hollows 204, 206, 208. A spring 210 biases the plate 192 clockwise about the support 194 and consequently, the position of the pin 200 in engagement with one of the hollows 204, 206, 208 limits the clockwise rotation of the plate 192 and thus determines the elevation of a pin 211 carried by plate 192. Pin 211 in turn determines the amount of line spacing in a manner that will be hereinafter described.

A pawl 212 (Fig. 3) is mounted on pin 214 which in turn is carried by the hook member 177. A spring 216 is wrapped around pin 214 and biases the pawl 212 normally clockwise about pin 214 and towards the teeth 218 of ratchet wheel 220, which in turn is mounted co-axially of and releasably secured to the platen in a well known manner. It will be seen that any pull on tape 184 will pull pin 183 down rotating hook member 177 clockwise about its support 179 thereby permitting spring 216 to bias pawl 212 clockwise about its support 214 and into engagement with the teeth 218 of the ratchet wheel 220. The extent of clockwise rotation of hook member 177, however (irrespective of the position of pin 200 and aperture 202), is determined by pawl 212 striking bracket 222. Subsequent release of tape 184 will permit the dog 186 to rotate arm 177 counterclockwise about its support pin 179 to restore it to its normal or rest position.

The pawl 212 has a shoulder 224 which is engageable with a tongue 226 of a U-shaped member 228, which in turn is supported at pin 183 with tape 184. The U-shaped member 228 is rotatable about pin 183 and it is also positioned for engagement with the pin 211 carried by plate 192. Consequently, as tension on tape 182 is released after a line spacing operation, the U-shaped member 228 strikes pin 211 and the outer extremity of tongue 226 strikes shoulder 224 of pawl 212, knocking it out of engagement with the teeth 218.

With this line spacing structure, single, double or triple line spacing is controlled by changing the position of pin 200 in aperture 202; i. e. as pin 200 is moved from hollow 204 to hollow 206, the elevation of pin 211 is increased and hence pawl 212 has a larger (double space) line spacing stroke. When in hollow 208, the line spacing

stroke is again increased (triple space) since the elevation of pin 211 has been increased. Obviously, the hollows 206, 208 are positioned to effect the desired line spacing operation.

While there have been shown and described and pointed out the fundamental novel features of the invention as applied to a preferred embodiment, it will be understood that various omissions and substitutions and changes in the form and details of the device illustrated and in its operation may be made by those skilled in the art without departing from the spirit of the invention. It is the intention, therefore, to be limited only as indicated by the scope of the following claims.

What is claimed is:

1. In a typewriter having a platen, a structure supporting feed rollers for cooperation with said platen, said structure comprising, in combination, a pair of elongated torsion springs extending parallel to said platen, clamping means engaging said torsion springs at spaced points for holding said springs from turning about their axes at such points, support arms fixed to said torsion springs at points spaced from said clamping means, said support arms extending from said springs to opposite sides of said platen, feed rollers carried by said support arms and engageable with said platen, cam means engageable with one of said support arms for rocking it away from said platen against the action of the one of said springs to which it is connected, and means interconnecting said support arms so that a rocking of said one of said support arms by said cam means causes a counter-rocking movement of another of said support arms extending to the opposite side of said platen.

2. The structure of claim 1 in which said cam means is formed on a first shaft extending parallel to said platen at one side of said torsion springs, means including a lever fixed to one end of said shaft for rotating the latter, a second shaft extending parallel to said platen at the opposite side of said springs, support brackets extending between said first and second shafts and having openings through which said torsion springs extend, and bushings fixed to said support arms and rotatably received within said openings.

3. The structure of claim 2 in which said clamping means comprises a bracket fixed to said second shaft and having flange portions closely adjacent one side of each of said springs, and screws engaging the opposite sides of said springs for holding the latter in place and adjusting the spring action.
